UNITED STATES PATENT OFFICE

2,010,382

RAILWAY CAR WALL

Arthur E. Small, Beverly Shores, Ind., assignor
to Union Metal Products Company, Chicago,
Ill., a corporation of Delaware

Application July 12, 1934, Serial No. 734,788

15 Claims. (Cl. 105—410)

The invention relates to railway freight cars and more particularly to end walls for open top cars, such as hopper or gondola cars.

The object of the invention is to provide an end wall for such cars which obtains substantially the maximum cubical capacity of the car (as far as the end wall thereof is concerned) without increasing the train length of the car and allows the ladder treads, handholds and part 10 of the brake mechanism to be applied in compliance with the existing safety appliance standards under the Interstate Commerce Commission Act.

These standards read as follows regarding "End ladder clearance". "No part of car above 15 end sills within thirty (30) inches from side of car, except buffer block, brake shaft, brake wheel, brake step or uncoupling lever shall extend to within twelve (12) inches of a vertical plane parallel with end of car and passing through the 20 inside face of knuckle when closed with coupler horn against the buffer block or end sill, and no other part of end of car or fixtures on same above end sills, other than exceptions herein noted, shall extend beyond the outer face of 25 buffer block."

The usual end wall of a car is a girder wherein the upper and lower frame members are the respective chords and the metallic plate wall is the web of the girder (as well as a retaining wall). A further object of the invention is to provide 30 means to stiffen this wall against deflection as a girder and against shifting lading as a retaining wall.

Another object is to provide integral stiffening means, such as corrugations, in the bulged parts of any improved end wall which are preferably positioned to transmit loads imposed thereon to the sloping webs of the end wall, which are beams in effect.

40 In the drawings:

Fig. 1 is a fragmentary view of a railway hopper car equipped with my improved end wall.

Fig. 2 is a section on line 2—2 of Fig. 1.

Fig. 3 shows the end wall plate of Fig. 1.

45 Fig. 4 is a fragmentary view of a railway gondola car equipped with my improved end wall.

Fig. 5 is a section on line 5—5 of Fig. 4.

Fig. 6 shows the end wall plate of Fig. 4.

50 Fig. 7 is a fragmentary view of a hopper car equipped with a modified form of my improved end wall.

Fig. 8 is a section on line 8—8 of Fig. 7.

Fig. 9 shows the end wall plate of Fig. 7.

55 Fig. 10 is a fragmentary view of a hopper car

equipped with another modified form of my improved end wall.

Fig. 11 is a section on line 11—11 of Fig. 10.

Fig. 12 shows the end wall plate of Fig. 10.

Fig. 13 shows an end wall plate of modified 5 construction.

Fig. 14 is a section on line 14—14 of Fig. 13.

Fig. 15 is a section on line 15—15 of Fig. 13.

Fig. 16 is a side elevation of Fig. 13.

Fig. 17 is a section on line 17—17 of Fig. 13. 10 Fig. 18 shows an end wall of modified construction.

Fig. 19 is a side elevation of Fig. 18.

Fig. 20 is a section on line 20—20 of Fig. 18.

Fig. 21 is a section on line 21—21 of Fig. 18. 15

Fig. 22 shows the brake mast end of a car equipped with my improved end.

Fig. 23 is a plan view of Fig. 22.

Fig. 24 shows the end wall of Fig. 22.

In the form of my invention illustrated in Figs. 20 1, 2 and 3 the end wall extends between and is secured to the corner posts 2 of a hopper car and extends between and is secured to the top chord 3 and the sloping floor sheet 4. The end posts 5 and corner posts 2 extend to the underframe of 25 the car and are supported thereby.

The dot and dash lines show the limitations prescribed by the safety appliance standards heretofore quoted designated for convenience as the central part 7, the left side part 8 and the 30 right side part 9. The drawings show the coupler 12, coupler horn 13, knuckle pulling surface 14 and striking casting face 15 and ladder rungs 16 referred to in the safety appliance standards.

I preferably bulge the end wall panel out from 35 the marginal portions 20 substantially to the safety appliance standards line at the central part 21 and right side part 22 thereof. The end ladder extends up to the top of the car and some of the rungs 16 of the ladder must necessarily be 40 opposite the left side part 23 of the end wall, therefore, I bulge the left side part 23 of the bulged central part of the end wall out as far as I may and still position the ladder rungs 16 in 45 their required position. It will be observed, therefore, that in hopper cars the central part 21, right part 22 and left part 23 of the bulged portion of the end wall may be in two distinct planes from the plane of the marginal portions.

In gondola cars the right side grab iron 26 is 50 opposite the end wall so that the same limitations apply thereto as apply to the ladder rungs 27 on the left side of the car, therefore, while the central bulged portion of the end wall may be relatively deep at its middle part (28), the two side 55

parts 29-30, while relatively shallow, will be substantially equal in depth and in substantially the same plane. Figs. 4, 5 and 6 show the end wall as applied to a gondola car wherein the parts 5 29-30 of the central bulged portion are substantially flat and in substantially the same plane, and are both in a plane spaced apart from the marginal portions 31 of the end wall. The lower part 32 of the marginal portions 31 is attached to 10 the end sill 33 of the car.

Figs. 7, 8 and 9 show a modification wherein the left part 35 is bulged outwardly as far as possible to allow the ladder rungs 36 to stay back of the safety appliance standards line, while the 15 right part 37 is bulged out to the safety appliance standards line. The middle part 38 is bulged still further out which is possible with cars equipped with 9 1/4" couplers. In other words, the bulged central part is in three separate planes.

20 Figs. 10, 11 and 12 show a modification similar to Figs. 7, 8 and 9 but wherein the left part 40 is in the same plane as the marginal portion 41. Numeral 42 is the right part and 43 is the middle part of the central bulged portion of the end 25 panel.

Figs. 13 to 17 inclusive show a modified construction wherein the side panels are each formed with an inwardly projecting rib 50 with one end merging into the adjacent marginal part 51 and 30 the other end merging into the side part adjacent the web 52 between the side part 53 and the central part 54. This rib does not project beyond the safety appliance standards line.

35 Figs. 18, 19, 20 and 21 show a modification wherein the bulged part is formed with corrugations 60 and 62. The corrugations stiffen the panel and in wide panels preferably extend vertically to carry the loads imposed on them by a 40 shifting cargo to the webs 61 of the panel which are beams. The corrugations preferably project inwardly.

45 On the brake end of some cars it may be necessary to extend the relatively shallow part of the bulged central portion nearer to the center line of the car so that the brake mechanism will be opposite the relatively shallow part rather than the relatively deep part because the safety appliance standards prescribe 22" as the maximum distance from the brake mast to the center line of 50 the car and also specify 4" from the pulling surface of the closed knuckle to the edge of the brake wheel and a minimum of 15" diameter brake wheel.

55 Figs. 22, 23 and 24 show a typical brake operating mechanism wherein the vertical shaft 70 is provided with a wheel 71 above the end wall of the car. The brake step 72 is provided for the operator. The relatively shallow part 73 of the bulged central portion extends to a line 74 60 between the brake shaft 70 and the center line 75 of the car, or in other words, to the oblique portion 76 separating the relatively shallow part 73 from the relatively deep part 71. The ladder runs are shown at 78.

65 The accompanying drawings illustrate the preferred form of the invention, though it is to be understood that the invention is not limited to the exact details of construction shown and described, as it is obvious that various modifications 70 thereof within the scope of the claims will occur to persons skilled in the art.

I claim:

75 1. In a railway car an end wall plate having a marginal portion and a central portion bulged outwardly from said marginal portion to increase

the cubical capacity of the car, the part of said central portion adjacent one side of the car being in a plane spaced apart from said marginal portion and the remainder of said central portion being still further spaced apart from said marginal portion. 5

2. In a railway car an end wall plate having a marginal portion and a central portion bulged outwardly from said marginal portion to increase the cubical capacity of the car, the part of said central portion adjacent one side of the car being substantially flat and in a plane spaced apart from said marginal portion and the remainder of said central portion being substantially flat and in a plane still further spaced apart from said marginal portion. 10

3. In a railway car an end wall plate having a marginal portion and a central portion bulged outwardly from said marginal portion to increase the cubical capacity of the car, the parts of said central portion adjacent the sides of the car being in a plane spaced apart from said marginal portion and the part of said central portion between the first mentioned parts being still further spaced apart from said marginal portion. 20

4. In a railway car an end wall plate having a marginal portion and a central portion bulged outwardly from said marginal portion to increase the cubical capacity of the car, the parts of said central portion adjacent the sides of the car being substantially flat and in a plane spaced apart from said marginal portion and the part of said central portion between the first mentioned parts being substantially flat and in a plane still further spaced apart from said marginal portion. 30

5. In a railway car an end wall plate having a marginal portion and a central portion bulged outwardly from said marginal portion to increase the cubical capacity of the car, the part of said central portion adjacent one side of the car being substantially flat and in a plane spaced apart from said marginal portion, the part of said central portion adjacent the other side of the car being in a plane spaced further apart from the marginal portion than the first mentioned part 45 and the part of said central portion between the first mentioned parts being substantially flat and in a plane still further spaced apart from said marginal portion. 55

6. In a railway car an end wall plate having a marginal portion and a central portion bulged outwardly from said marginal portion to increase the cubical capacity of the car, the part of said central portion adjacent one side of the car being in the plane of the marginal portions, the part 55 of said central portion adjacent the opposite side of the car being in a plane spaced apart from said marginal portion and the part of said central portion between the first mentioned parts being in a plane still further spaced apart from said marginal portion. 60

7. In a railway car an end wall plate having a marginal portion and a central portion bulged outwardly from said marginal portion to increase the cubical capacity of the car, the part of said central portion adjacent one side of the car being in a plane spaced apart from said marginal portion and the remainder of said central portion being in a plane still further spaced apart from said marginal portion, said part being provided 70 with an inwardly projecting rib having one end merging into the adjacent marginal portion and the other end thereof merging into said part adjacent the opposite side of said part. 75

8. In a railway car an end wall plate having a 75

5 marginal portion and a central portion bulged outwardly from said marginal portion to increase the cubical capacity of the car, the parts of said central portion adjacent the sides of the car being 5 in a plane spaced apart from said marginal portion and the part of said central portion between the first mentioned parts being in a plane still further spaced apart from said marginal portion, said parts being each provided with an 10 inwardly projecting rib having one end merging into the adjacent marginal portion and the other end thereof merging into said part adjacent the opposite side of said part.

9. In a railway car, an end wall having marginal 15 portions and a central portion therebetween formed into an outwardly projecting bulge to increase the cubical capacity of the car, a substantial part of the bulge adjacent one side of the car being relatively shallow and substantially parallel to said marginal portions and the remainder of the bulge being relatively deep.

10. In a railway car, an end wall having marginal portions and a central portion therebetween formed into an outwardly projecting bulge to increase the cubical capacity of the car, substantial parts of the bulge adjacent the side of the car being relatively shallow and substantially parallel to said marginal portions and the remainder of the bulge being relatively deep.

11. In a railway car, an end wall having marginal portions and a central portion therebetween formed into an outwardly projecting bulge to increase the cubical capacity of the car, a substantial part of the bulge adjacent one side of the car being relatively shallow and substantially parallel to said marginal portions and the remainder of the bulge being relatively deep, and a handhold secured to said shallow part.

12. In a railway car, an end wall having marginal portions and a central portion therebetween formed into an outwardly projecting bulge to in-

crease the cubical capacity of the car, substantial parts of the bulge adjacent the side of the car being relatively shallow and substantially parallel to said marginal portions and the remainder of the bulge being relatively deep, and handholds secured to said shallow parts.

13. In a railway car, an end wall having marginal portions and a central portion therebetween formed into an outwardly projecting bulge to increase the cubical capacity of the car, a substantial part of the bulge adjacent one side of the car being relatively shallow and substantially parallel to said marginal portions and the remainder of the bulge being relatively deep, said shallow part provided with an inwardly projecting corrugation with its ends merging therewith.

14. In a railway car, an end wall having marginal portions and a central portion therebetween formed into an outwardly projecting bulge to increase the cubical capacity of the car, a substantial part of the bulge adjacent one side of the car being relatively shallow and substantially parallel to said marginal portions and the remainder of the bulge being relatively deep, said deep part provided with an inwardly projecting corrugation with its ends merging therewith.

15. In a railway car, an end wall having marginal portions and a central portion therebetween formed into an outwardly projecting bulge to increase the cubical capacity of the car, a substantial part of the bulge adjacent one side of the car being relatively shallow and substantially parallel to said marginal portions and the remainder of the bulge being relatively deep, said shallow part provided with an inwardly projecting corrugation with its ends merging therewith and said deep part provided with an inwardly projecting corrugation with its ends merging therewith.

ARTHUR E. SMALL. 40
